UNITED STATES PATENT OFFICE.

WILLIAM S. GUTHRIE, OF TERRELL, TEXAS.

FUEL-SUPPLY APPARATUS.

1,359,592.

Specification of Letters Patent. Patented Nov. 23, 1920

Application filed July 5, 1919. Serial No. 308,809.

To all whom it may concern:

Be it known that I, WILLIAM S. GUTHRIE, a citizen of the United States, and residing at Terrell, in the county of Kaufman and State of Texas, have invented a new and Improved Fuel-Supply Apparatus, of which the following is a specification.

This invention relates to a fuel supply apparatus for causing liquid fuel to flow to the carbureter of an internal combustion engine from a supply tank positioned below the level of the carbureter.

The object of the invention is to provide an efficient liquid fuel supply apparatus for causing liquid fuel to flow to the carbureter as fast as demanded by the engine when running under the most trying conditions. Another object is to eliminate annoyances formerly had with fuel supply apparatus. A further object is to eliminate the intermediate storage reservoir between the carbureter reservoir and the vacuum chamber, as used in connection with other fuel supply devices.

Various forms of fuel supply apparatus as used in the past have had more or less objectionable features which the present invention is intended to eliminate; such for instance as the danger of bursting the tank of the pressure feed type where compressed air in the supply tank forces the fuel to the carbureter; and the failure of the vacuum feed type to supply the fuel when ascending long hills in an automobile; and the breaking of the diaphragms of other types.

The invention comprises a storage reservoir, a supply tank, an intermediate chamber forming a passage between the supply tank and the reservoir, preferably air pressure varying means for varying the air pressure in the intermediate chamber, so that sub-atmospheric pressure and super-atmospheric pressure is created in said chamber intermittently when the engine is in operation, and thereby causing the liquid to be sucked into said chamber from the supply tank, and forced therefrom into the storage reservoir.

One feature of the invention resides in having a float arranged in the storage reservoir so that the float controls the pumping of the fuel from the source of supply by causing the flow to decrease with the rising of the float, and having an inlet and an outlet check valve for the intermediate or suc-

tion chamber, the said check valves being so positioned and arranged that the fuel flows in one direction only through the same throughout the operation of the fuel supply apparatus.

The invention also consists in matters hereinafter set forth and more particularly pointed out in the claims.

The nature of the invention is such that the usual carbureter float chamber may be employed as the storage reservoir since a uniform level of the liquid may be maintained in the latter; but when desired the storage reservoir of the fuel supply apparatus may be employed as an auxiliary supply reservoir to feed the float chamber, or other reservoir of the carbureter.

Figure 1 illustrates the fuel supply system and shows a sectional view of one form of storage reservoir and intermediate chamber, and the arrangement of the check valves. Fig. 2 is an enlarged sectional view of the section adjacent the check valve 22. Fig. 3 is an enlarged view of the valve 15. Fig. 4 shows a sectional view of a modified form of intermediate chamber, and the fuel passages shown diagrammatically. Fig. 5 is a view on line 5—5 of Fig. 4, showing the arrangement of the check valves and passages in practical form.

The air pressure varying means as shown may be the combustion chamber of an internal combustion engine, or it may be a pump which consists of a sliding piston positioned in a cylinder so that when the piston is moved downward it causes the air pressure in the cylinder to fall below that of atmospheric pressure, and the upward movement of the piston causes the air pressure in the cylinder to rise above atmospheric pressure.

It is preferred that the piston be operated in some manner by the engine which is to be fed with fuel by the fuel supply system; and when desired it is intended that the usual combustion chamber of an internal combustion engine may be employed as the air pressure varying means for varying the air pressure in the intermediate chamber; in fact it is intended that any known air pressure varying means may be employed to accomplish this purpose. The air pressure varies widely in the crank case of some engines, and in some instances the crank case may be employed as the air pressure varying means. It is preferred that

the engine which is to be supplied with fuel be employed to operate the air pressure varying means.

In Fig. 1, the pipe 1 connects the cylinder 2 with the intermediate chamber 3. The downward movement, or suction stroke of the piston 4 causes the exhaust of air from the chamber 3. The air thus flowing from the chamber 3 passes up through the passages 5, 6, 7, 8 and 9 to the pipe 1 through which it flows to the cylinder 2. The ball check valve 10 opens the passage 8 when the piston is moving downward to provide free access of the suction to the chamber 3, and when the piston is moving upward, compressed air from the cylinder 2 is forced into the intermediate chamber 3 through the by-pass passage 7, which latter passage is small enough to prevent excessive compression forming in the chamber 3, and yet suffices for the purpose of forcing the liquid therefrom, as hereinafter described.

The pipe 11 connects the supply tank 12 with the intermediate chamber 3. The suction stroke of the piston 4 creates a partial vacuum in the chamber 3 and causes liquid from the tank 12 to pass up the pipe 11 and flow through the passage 13 and down the passages 14 around the valve 15 and through the passage 16, then up past the ball check valve 17 and through the ports 18 to the chamber 3. When the chamber 3 is filled to a predetermined level the float 19 rises up and presses against the collar 20 on the valve 21 and causes the latter to raise and close off the passage 8, and thus prevents the suction from sucking the liquid up into the cylinder 2. The chamber 3 as shown is of cylindrical shape, and the float 19 is of a piston like nature. The valve 10 may be eliminated when the float 19 is made to fit closely to the wall of the vacuum chamber 3 so that the fire from the exhaust is prevented from reaching the liquid fuel below the float 19.

The compression stroke of the piston 4 causes air to flow back into the chamber 3 through the pipe 1, the by-pass 7 and passages 6 and 5, and this back pressure forces the liquid out of the chamber 3 through the passage 22 and past the ball check valve 23 to the chamber 24 through the port 25, and down the tubular passage around the coiled spring 26 to the tube 27, down through which it flows and passes out into the reservoir 28 through the ports 29. The coiled spring 26 holds the check valve 23 up against its seat to prevent leakage of air to the chamber 3 when the piston 4 is moving downward, and the check valve 17 prevents the back pressure or compression reaching the passages leading from the chamber 3 to the supply tank 12.

The float 30 controls the level of the liquid in the reservoir 28 by rising up and clos-

ing the valve 15 so that the amount of liquid flowing from the supply tank 12 is restricted to the amount flowing from the reservoir 28 to the engine. It will thus be apparent that the fuel maintains a uniform level in the reservoir 28 when the engine is in operation. After the reservoir 28 is once filled to its normal level the valve 15 may be almost entirely closed and the amount of liquid thereafter flowing into the intermediate chamber 3 may not be enough to cause the float 19 to rise sufficiently to close the valve 21.

The storage reservoir that forms a passage between the vacuum chamber and the constant level reservoir of the carburetor, as used in connection with other fuel supply devices, may be eliminated, when the reservoir 28 is positioned in respect to the carburetor fuel jets (not shown), so that when the engine is at rest the reservoir 28 is not emptied by the fuel overflowing said jets.

The reservoir 28 may be made integral with the carburetor body as shown in Fig. 1, the said body being partly broken off to the right side of the reservoir 28.

The fuel passage 29^a conveys the fuel from the reservoir 28 to the carburetor jets in the usual manner, and the fuel supply may be restricted at the discharge jets (not shown) or at any point between the discharge jets and the reservoir 28 by a calibrated jet, or as by having a needle valve 29^b to control the flow of the fuel.

The valve 21 as shown is guided at both ends and it is loosely extended entirely through the float 19 and guides the latter to prevent it touching the walls of the chamber 3. The float 19 has considerable vertical movement without imparting movement to the valve 21 which obviously minimizes the wear to the valve and its guiding means.

In Fig. 4, a ball float 19' controls the communication between the intermediate chamber 3' and the air pressure varying cylinder 2', a valve 21' being adapted to close the suction passage 8' when the float rises to a predetermined level. Excessive compression in the chamber 3' may be prevented by a check valve 31 which is held seated by a coiled spring 32 to prevent leakage of air when the piston 4' is moving downward.

The tension of the spring 32 may be adjusted by means of an adjusting screw 33 and lock nut 34. When the compression in the chamber 3' is sufficient to overcome the spring tension against the ball valve 31, air will flow out to the atmosphere through the passages 35 and 36. The by-pass passage 37 around the needle valve 21' and the pipe 1', affords means of communication between the air pressure varying means and the chamber 3'.

When the liquid is sucked into the cham-

ber 3' its flow is controlled by the valve 15' and float 30'. The liquid enters at 38 and passes down around the valve 15' to the passage 16' then up past the check valve 17' and into the chamber 3' through the port 39. When the liquid fills the chamber 3' to a predetermined level the float 19' rises and the coiled spring 40 then lifts the valve 41 so that the compression stroke of the piston 1' will force the liquid out under the head of the valve 41 and through the passage 42 past the check valve 43 and down into the storage reservoir 28', through the passage 44. The latter passage is positioned to one side of the float 30' so that the inflowing liquid is prevented from disturbing the float. When the liquid is thus discharged from the chamber 3', the float 19' is lowered and its weight overcomes the tension of the spring 40 and causes the valve 41 to close to prevent leakage of compression. The valve 41 may be especially desirable when employing the combustion chamber of an internal combustion engine for the air pressure varying means. Sometimes the float 19' may act in place of the valve 41.

In Fig. 5 the liquid passages leading to and from the chamber 3' are shown in a more compact form, and this figure clearly shows the same to be in a form which is easily manufactured, the passages 16', 39, 42, and 44 being drilled from the exterior of the body and screw plugs being employed to close the external ends of the several passages.

The construction of this fuel supply apparatus may be widely varied from that shown without departing from the scope of the invention; and the various valves 10, 31 and 41 such as shown, may not always be needed to cause the proper functioning of the fuel supply apparatus; and the absence of either or all of said valves does not exclude the structures from being within the scope of the invention. The various valves may also be shifted from one structure to the other in order to obtain the proper functioning of the device.

This invention may be applied to any other device where a liquid supply system may be used, as well as for the purpose above described.

The passages 35 and 36 and the parts 32, 33 and 34 should be eliminated when the valve 31 is eliminated.

A lever 45 as shown in Fig. 4 may be employed to increase the pressure of the float on the valve 15 shown in Fig. 1 when desired.

I claim:—

1. A fuel supply apparatus for an internal combustion engine comprising a source of supply, a storage reservoir, a float in said storage reservoir to control the fuel level therein, an intermediate chamber forming a

passage between the source of supply and the storage reservoir, air pressure varying means for varying the air pressure in the intermediate chamber from sub-atmospheric pressure to super-atmospheric pressure, so that the sub-atmospheric pressure sucks fuel into said intermediate chamber and the super-atmospheric pressure forces the fuel into said storage reservoir, and means to control the communication between the air pressure varying means and said intermediate chamber.

2. A fuel supply apparatus comprising a source of supply, a storage reservoir, a float in said storage reservoir to control the fuel level therein, an intermediate chamber forming a passage between the source of supply and the storage reservoir, air pressure varying means for varying the air pressure in the intermediate chamber from sub-atmospheric to super-atmospheric pressure, so that the sub-atmospheric pressure sucks fuel into said intermediate chamber and the super-atmospheric pressure forces the fuel into said storage reservoir, and means to automatically control the communication between the air pressure varying means and said intermediate chamber.

3. A fuel supply apparatus for an internal combustion engine comprising a source of supply, a storage reservoir, a float in said storage reservoir to control the fuel level therein, an intermediate chamber forming a passage between the source of supply and the storage reservoir, air pressure varying means for varying the air pressure in the intermediate chamber from sub-atmospheric pressure to super-atmospheric pressure, so that the sub-atmospheric pressure sucks fuel into said intermediate chamber and the super-atmospheric pressure forces the fuel into said storage reservoir, and a float in the intermediate chamber to control the communication between the air pressure varying means and said intermediate chamber.

4. A fuel supply apparatus for an internal combustion engine comprising a source of supply, a storage reservoir, a float in said storage reservoir to control the fuel level therein, an intermediate chamber forming a passage between the source of supply and the storage reservoir, air pressure varying means for varying the air pressure in the intermediate chamber from sub-atmospheric pressure to super-atmospheric pressure during the operation of said engine, so that the sub-atmospheric pressure sucks fuel into said intermediate chamber and the super-atmospheric pressure forces the fuel into said storage reservoir, and a float in the intermediate chamber to control the communication between the air pressure varying means and said intermediate chamber.

5. A fuel supply apparatus for an inter-

nal combustion engine comprising a source of supply, a storage reservoir, a float in said storage reservoir to control the fuel level therein, an intermediate chamber forming a 5 passage between the source of supply and the storage reservoir, air pressure varying means for varying the air pressure in the intermediate chamber from sub-atmospheric pressure to super-atmospheric pressure, so 10 that the sub-atmospheric pressure sucks fuel into said intermediate chamber and the super-atmospheric pressure forces the fuel into said storage reservoir, said air pressure varying means being operated by said engine, and a float in the intermediate chamber to control the communication between the air pressure varying means and said intermediate chamber.

6. A fuel supply apparatus comprising a 20 source of supply, a storage reservoir, an intermediate chamber forming a passage between the source of supply and the storage reservoir, a non-return valve to prevent fluid flowing to the source of supply from the 25 intermediate chamber, air pressure varying means for varying the air pressure in the intermediate chamber from sub-atmospheric to super-atmospheric pressure, means to control the communication between the air pressure 30 varying means and said intermediate chamber, and means to control the communication between the source of supply and the said intermediate chamber.

7. A fuel supply apparatus comprising a 35 source of supply, a storage reservoir, an intermediate chamber forming a passage between the source of supply and the storage reservoir, a non-return valve to prevent fluid flowing to the source of supply from the 40 intermediate chamber, air pressure varying means for varying the air pressure in the intermediate chamber from sub-atmospheric to super-atmospheric pressure, a float in the intermediate chamber to control the communication 45 between the air pressure varying means and said intermediate chamber, and means to control the communication between the source of supply and the said intermediate chamber.

50 8. A fuel supply apparatus comprising a source of supply, a storage reservoir, an intermediate chamber forming a passage between the source of supply and the storage reservoir, air pressure varying means for 55 varying the air pressure in the intermediate chamber from sub-atmospheric to super-atmospheric pressure, means to control the communication between the air pressure varying means and said intermediate chamber, and a float in the storage reservoir to control the communication between the source of supply and the said intermediate chamber.

60 9. A fuel supply apparatus comprising a 65 source of supply, a storage reservoir, an

intermediate chamber forming a passage between the source of supply and the storage reservoir, air pressure varying means for varying the air pressure in the intermediate chamber from sub-atmospheric to super-atmospheric pressure, a float in the intermediate chamber to control the communication between the air pressure varying means and said intermediate chamber, and a float in the storage reservoir to control the communication between the source of supply and the said intermediate chamber.

10. A fuel supply apparatus comprising a source of supply, a storage reservoir, an intermediate chamber forming a passage between the source of supply and the storage reservoir, air pressure varying means for varying the air pressure in the intermediate chamber from sub-atmospheric to super-atmospheric pressure, a float in said storage 80 reservoir to control the level of the fuel therein, and means to prevent excessive compression forming in said intermediate chamber.

11. A fuel supply apparatus comprising a 90 source of supply, a storage reservoir, an intermediate chamber forming a passage between the source of supply and the storage reservoir, air pressure varying means for varying the air pressure in the intermediate 95 chamber from sub-atmospheric to super-atmospheric pressure, and means to prevent air flowing from the intermediate chamber to said storage reservoir.

12. A fuel pumping apparatus having 100 communication with an internal combustion engine, a combustion chamber for said engine, a fuel reservoir, a vacuum chamber for receiving fuel, a connection between said vacuum chamber and said combustion chamber, said connection being closed to prevent admission of air from the atmosphere and so arranged that the pressure created in said combustion chamber causes fuel to be forced into said reservoir from said vacuum chamber, a float in said reservoir, and a valve having communication with said float so as to control the pumping of the fuel, the flow 110 of fuel between said vacuum chamber and said reservoir being unresisted by said valve. 115

13. A fuel pumping apparatus having communication with an internal combustion engine including a compression chamber, means for creating super-atmospheric pressure in said compression chamber, a fuel 120 reservoir, a vacuum chamber for receiving fuel, a connection between said vacuum chamber and said compression chamber, said connection being closed to prevent admission of air from the atmosphere and so arranged that the pressure created in said compression chamber causes fuel to be forced into said reservoir from said vacuum chamber, a float in said reservoir, and a valve 125 communicating with said float so as to con- 130

trol the pumping of the fuel, the flow of fuel between said vacuum chamber and said reservoir being unresisted by said valve.

14. A fuel supply apparatus for an internal combustion engine including a storage reservoir and a vacuum chamber forming a passage between a source of supply and the storage reservoir, said vacuum chamber communicating with a combustion chamber of said engine so that the pressure created in said engine combustion chamber causes liquid fuel to be forced from said vacuum chamber and into said storage reservoir, said vacuum chamber being of cylindrical shape and having a reciprocating device therein preventing the liquid fuel rising above the top of said vacuum chamber, and a float in said storage reservoir controlling the fuel level therein.

20 15. A fuel pumping apparatus having a storage reservoir and a vacuum chamber forming a passage between a source of liquid fuel supply and said storage reservoir, means for pumping liquid fuel from said source of supply to the storage reservoir by way of said vacuum chamber, means to prevent the return of the fuel to the vacuum chamber from said storage reservoir in the operation of the pumping apparatus, said vacuum chamber being substantially sealed to prevent an appreciable amount of air entering the same in the operation of the pumping apparatus, the flow of the fuel to the storage reservoir being 35 under the influence of pressure greater than atmospheric pressure, and a float in the storage reservoir to control the pumping of the fuel.

16. A fuel pumping apparatus having a storage reservoir and a vacuum chamber forming a passage between a source of liquid fuel supply and said storage reservoir, means for pumping liquid fuel from said source of supply to the storage reservoir by way of said vacuum chamber, means to prevent the return of the fuel to the vacuum chamber from said storage reservoir in the operation of the pumping apparatus, the flow of fuel to the storage reservoir being under the influence of pressure greater than that of the atmosphere, a float in the storage reservoir, a valve controlled by said float so as to control the pumping of the fuel, said valve being so positioned and arranged that its opening movement is unassisted by super-atmospheric pressure.

17. A fuel supply apparatus for internal combustion engines including a suction chamber or passageway provided with inlet and outlet valves, a storage reservoir, a suction device communicating with said passageway which exerts suction on said inlet valve to cause fuel to enter said passageway,

said suction device being so arranged that it exerts pressure on said outlet valve intermittently when the engine is in operation so as to force the fuel out of said passageway and into a storage reservoir, said valves being so arranged and controlled that the fuel flows in one direction only through each of said valves in the operation of the engine, a float in said reservoir to control the level of the fuel therein, said passageway being substantially sealed to prevent the admission of an appreciable amount of air in the operation of the engine.

18. A fuel supply apparatus for internal combustion engines including a suction chamber or passageway provided with inlet and outlet valves, a carburetor reservoir, a suction device communicating with said passageway which exerts suction on said inlet valve to cause fuel to enter said passageway, said suction device being so arranged that it exerts pressure on said outlet valve intermittently when the engine is in operation so as to force the fuel out of said passageway and into said carburetor reservoir, said valves being so arranged and controlled that the fuel flows in one direction only through each of said valves in the operation of the engine, a float in said reservoir to control the level of the fuel therein, said passageway being substantially sealed to prevent the admission of an appreciable amount of air in the operation of the engine, and a needle valve to control the flow from the carburetor reservoir.

19. A fuel supply apparatus including a storage reservoir, a source of supply, an intermediate chamber communicating with said storage reservoir and the source of supply, means for reducing the air pressure in said intermediate chamber for lifting fuel thereto from said source of supply, a float in the intermediate chamber to control the communication between the latter chamber and the air pressure reducing means, and a float in the storage reservoir to control the communication between the source of supply and the intermediate chamber.

20. A fuel supply apparatus comprising a source of supply, a storage reservoir, an intermediate chamber forming a passage between the source of supply and the storage reservoir, means for reducing the air pressure in the intermediate chamber for lifting fuel thereto from the supply tank, means to control the communication between the air pressure reducing means and said intermediate chamber, and a float in the storage reservoir to control the communication between the source of supply and the said intermediate chamber.
